(57) **CLAIM**

I claim the ornamental design for a pattern for a vehicle grille, as shown and described.

DESCRIPTION

A portion of the disclosure of this patent document contains material which is subject to copyright protection. The copyright owner has no objection to the facsimile reproduction by anyone of the patent document or the patent disclosure as it appears in the Patent and Trademark Office patent file or records, but otherwise reserves all copyright rights whatsoever.

FIG. 1 is an enlarged fragmentary front elevational view illustrating a pattern for a vehicle grille embodying my new design, with broken lines indicating an indeterminate length and width of the grille and forming no part of the design;

FIG. 2 is a sectional view taken along line 2—2 of FIG. 1, shown only to illustrate one possible shape of the grille, although the shape of the grille does not form any part of the design;

FIG. 3 is a front elevational view shown only to illustrate one possible shape of a grille having the pattern of the claimed design, with a border of the possible shape being delineated by broken lines, the shape of the grille and the border do not form any part of the claimed design; and,

FIG. 4 is a sectional view taken along line 4—4 of FIG. 3, shown only to illustrate one possible shape of a grille having the pattern of the claimed design, the shape of the grille and the border do not form any part of the claimed design.

The left, right, rear and top and bottom elevational views are omitted because they do not necessarily show the claimed design of a pattern for a vehicle grille. The broken line disclosure, as well as the shading, are for illustrative purposes only and forms no part of the claimed design.
